Primary Examiner — Kevin Rudzinski(74) *Attorney, Agent, or Firm* — Fenwick & West LLP(57) **CLAIM**

We claim the ornamental design for a display panel of a programmed computer system with a graphical user interface, as shown and described.

DESCRIPTION

The FIGURE is a front view of an embodiment of a display panel of a programmed computer system with a graphical user interface.

The broken line showing of a display panel and portions of the graphical user interface is included for the purpose of illustrating environmental structure; the broken lines form no part of the claimed design.
